DRYING APPARATUS

Joseph Ettl, Plainfield, N. J., assignor to Pot-
devin Machine Company, Brooklyn, N. Y., a
corporation of New York

Application May 22, 1936, Serial No. 81,251

4 Claims. (Cl. 34—12)

This invention relates to drying apparatus and is particularly directed to a device for generating heat to heat air which is then circulated through a drying chamber or oven for the purpose of 5 drying or heating articles or material passed through the ovens on conveyors.

The present invention has for one of its objects the provision of a device of the character indicated comprising a novel arrangement of parts 10 whereby complete and uniform drying or heating of the articles or material is readily accomplished.

Further objects of the present invention will be manifest from the following detailed description and the accompanying drawings, in which 15 drawings:

Fig. 1 is a plan view of my improved device partly broken away to expose the interior construction;

Fig. 2 is a sectional view on line 2—2 of Fig. 1;

Fig. 3 is a sectional view on line 3—3 of Fig. 1;

Fig. 4 is a sectional view on line 4—4 of Fig. 3;

Figs. 5 and 6 are, respectively, plan and sec-
tional views of a modified form of heat gener-
ating chamber.

Referring to the drawings in detail, 1 designates a heat chamber wherein air is heated, the heated air being passed to a drying chamber or oven 2 which is in communication with the heat chamber 1. These chambers may be supported 20 on girders or platform 3 suspended from a ceiling 4 by means of struts 5 or supported in any other suitable manner.

The heat chamber 1 has a combustion com-
partment 6 provided with a plurality of burners 35 7. The roof or top wall R of the combustion com-
partment is shaped to provide a plurality of flues 8, 9, 10, 11 and 12 directly above each burner.

Within the heat chamber 1 is a pair of spaced 40 walls 13 and 14 extending horizontally and com-
municating at one side of the chamber with a
pair of vertical walls 15 and 16 and at the other
side with another pair of vertical walls 17 and
18. The walls 16 and 18 are provided with ex-
haust pipes or ducts 19 and 20, respectively.

The central flue 10 of the group of flues above 45 mentioned extends above the horizontal wall 14 and is provided with laterally extending flues
or conduits 10' extending into the space between
the walls 13 and 14.

The upper ends of the flues 8, 9, 11 and 12 50 have short pipes 26 projecting upwardly into this same space. It is through these pipes or con-
duits 10' and 26 that the products of combustion
pass into a compartment formed by the said
spaced walls 13 and 14, the products of combus-

tion in this compartment passing downwardly between the vertical spaced walls 15, 16 on one side and 17, 18 on the other side and through the exhaust pipes 19 and 20.

It will be appreciated that it would not be de-
sirable to utilize the products of combustion in 5
the drying chamber or oven 2 due to the gases
and impurities it contains, consequently the ex-
haust ducts 19 and 20 may lead to waste or if
desired may be recirculated in the heat cham- 10
ber 6.

The air which is employed and utilized in the 15 drying chamber or oven is fresh clean air which is heated by circulating the same in contact with the outside walls of the flues 8, 9, 10, 11 and 12 and the walls 13, 16 and 17 of the heat compart-
ment, as will be described presently.

Extending downwardly from the wall 14 be-
tween the flues 8 and 9 and 11 and 12 I provide 20
baffles 22 and 23, respectively. I also provide
baffles 20 and 21 extending downwardly from
the top wall 25 of the chamber 1 between the
flues 9 and 10 and the flues 10 and 11, respec-
tively. The baffles 20 and 21 are provided with open-
ings 24 adjacent their upper ends to accommo- 25
date the laterally extending flues 10', as will be
seen from Fig. 1.

The drying air is recirculated from the dry-
ing chamber or oven by means of a blower 30
driven by a motor 31. This blower is located in 30
a blower housing 32 which communicates with
the heating chamber through a conduit formed
by vertical walls 33 and 34 which communicates
with the intake conduit 35 shown in Fig. 4. An
auxiliary air inlet 36 is located in this intake 35
conduit 35 for the admission of fresh auxiliary
air to the heating chamber. This inlet is con-
trolled by a manually operated damper 37.

The air entering the intake conduit travels 40
downwardly between the baffles 20 and 21 where
the same is divided by the flue 10 so that part will
flow to the right and part to the left of the cham-
ber, as viewed in Fig. 4.

This air will pass in a staggered path between 45
the downwardly extending baffles 22 and 23 and
the upwardly extending flues 8, 9, 11 and 12 in
the direction of the arrows shown in Fig. 4, the
air on one side passing upwardly between the
walls 16 and 40 and on the other side between the
walls 18 and 41 to outlet conduit 42 (shown in 50
Fig. 1) which in turn communicates with the dry-
ing chamber 2.

The drying chamber 2 receives the heated air 55
from the heating chamber through the outlet
conduit 42 as just described. This conduit com-

municates with a longitudinally extending conduit 50 having a plurality of spaced openings 51 in the bottom wall or partition 52 thereof. Below the partition 52 is another wall or partition 53. The space formed by the partitions 52 and 53 I shall call the equalizing chamber inasmuch as the air is evenly distributed therein, as will be described presently. The partition 53 has a plurality of transversely extending spaced slots 54 formed therein.

The air passing from the outlet conduit 42 enters the space between the walls or partitions 52 and 53 through the spaced openings 51 which serve to distribute the air evenly. The air passes from this space to the drying compartment or oven 58 through the slots 54, each of which has a pair of flanges supporting screens 55 which further evenly distribute the air before the same is directed upon articles on the conveyor 56 which is located below the wall 53.

After the heated air passes the conveyor it is drawn through conduits 60 and 61 back to the blower housing 32 where it is again circulated.

It will be appreciated from the foregoing that I have provided a structure wherein the air to be treated is circulated in a long irregular path in close contact with heated flues and baffles and is thence passed to an equalizing chamber where the same is equalized or evenly distributed before application to the articles being treated, and finally recirculated.

The modified form of heating chamber illustrated in Figs. 5 and 6 likewise provides a long irregular path for the air being heated. In this form the air enters the chamber through inlet conduit 70 and passes around flues 71, 72, 73, 74 and 75 and thence to the drying chamber through outlet conduit 76, as in the form shown in Figs 1 to 4, inclusive.

This form is also provided with burners 76, 77, 78, 79 and 80 for the flues 71, 72, 73, 74 and 75, respectively.

The products of combustion from the flues pass through the conduit 80 formed by the horizontal spaced walls 81 and 82 to the vertical spaced walls 83 and 84 and out through exhaust outlet 85.

It is to be understood that various changes and modifications may be made in the structure herein illustrated and described without departing from the spirit and scope of my invention.

What I claim is:—

1. In apparatus of the class described including an external heater, a drier comprising in combination an inlet for admitting heated air from said heater to the drier, a partition in said drier dividing the drier into two compartments disposed in superimposed relation, said partition being provided with a plurality of slots, a screen adjacent each of said slots, thereby to provide an equalizing chamber and a drying chamber with the equalizing chamber immediately adjacent the heated air inlet, means for supporting articles in the drying chamber, said slots extending transversely of the article supporting means, and

means for circulating the heated air through said transverse slots and screens and past the articles carried by said supporting means.

2. In apparatus of the class described including an external heater, a drier comprising in combination a longitudinally extending heated air duct for admitting heated air from said heater to said drier, a conduit at an angle to said duct, said duct communicating with said conduit intermediate the ends of the conduit, said conduit being provided with a plurality of openings in its lower wall, a partition in said drier dividing the same into two compartments, said partition being provided with a plurality of slots thereby to provide an equalizing chamber and a drying chamber with the equalizing chamber immediately adjacent the openings in said conduit, means for supporting articles in the drying chamber, said slots extending transversely of the article supporting means, and means for circulating heated air through said openings and slots and into contact with the articles carried by said supporting means.

3. In apparatus of the class described including an external heater, a drier comprising in combination a longitudinally extending heated air duct for admitting heated air from said heater to said drier, a conduit at an angle to said duct, said duct communicating with said conduit intermediate the ends of the conduit, said conduit being provided with a plurality of openings in its lower wall, a partition in said drier dividing the same into two compartments, said partition being provided with a plurality of slots thereby to provide an equalizing chamber and a drying chamber with the equalizing chamber immediately adjacent the openings in said conduit, means for supporting articles in the drying chamber, said openings and said slots extending transversely of the article supporting means, and means for circulating heated air through said openings and slots and into contact with the articles carried by said supporting means.

4. In apparatus of the class described including an external heater, a drier comprising in combination a longitudinally extending heated air duct for admitting heated air from said heater to said drier, a conduit at an angle to said duct, said duct communicating with said conduit intermediate the ends of the conduit, said conduit being provided with a plurality of openings in its lower wall, a partition in said drier dividing the same into two compartments, said partition being provided with a plurality of transverse slots, a screen for each of said slots, thereby to provide an equalizing chamber and a drying chamber with the equalizing chamber immediately adjacent the openings in said conduit, means for supporting articles in the drying chamber, said slots extending transversely of the article supporting means, and means for circulating heated air through said openings, slots and screens and into contact with the articles carried by said supporting means.

JOSEPH ETTL.
